UNITED STATES PATENT OFFICE.

FRANZ X. WAGNER, OF NEW YORK, N. Y., ASSIGNOR TO UNDERWOOD TYPEWRITER COMPANY, OF NEW YORK, N. Y., A CORPORATION OF NEW JERSEY.

RIBBON MECHANISM FOR TYPE-WRITERS.

SPECIFICATION forming part of Letters Patent No. 763,938, dated June 28, 1904.

Original application filed April 28, 1903, Serial No. 154,696. Divided and this application filed September 22, 1903. Serial No. 174,163 (No model.)

To all whom it may concern:

Be it known that I, FRANZ X. WAGNER, a citizen of the United States, and a resident of the borough of the Bronx, city, county, and State of New York, have invented certain new and useful Improvements in Ribbon Mechanism for Type-Writers, of which the following is a specification.

My present invention pertains to type-writing and similar machines, and particularly relates to mechanism for actuating the ribbon usually employed in such machines.

This application embodies subject-matter divided from my application for patent filed April 28, 1903, Serial No. 154,696.

In carrying my invention into effect I provide a frame which is preferably pivoted at a point close to the general plane of arrangement of the key-levers, the pivot for said frame lying parallel to said plane and transverse of said key-levers. I prefer that the said pivot of said frame be located adjacent to the pivot or pivots of said key-levers. I provide a universal bar upon said frame remote from the pivot thereof and substantially parallel to said pivot and said general plane of arrangement of the key-levers, which universal bar is adapted to be operated upon the actuation of any one of said key-levers. From this universal-bar frame I actuate the devices which feed the ribbon and place it in position for the impression of the type when a key is depressed and remove the ribbon to disclose the printed letter to the operator upon the release of said key. The novel form, disposition, and combination of these devices constituting my present invention will be hereinafter fully described and then pointed out in the claims.

In the drawings, Figure 1 is a sectional elevation taken from front to rear at about the center of a type-writing machine embodying my invention. Fig. 2 is a detail of the ribbon-feed mechanism, showing the feed-controlling means. Fig. 3 is a similar detail showing one ratchet-and-pawl mechanism and portions of the universal bar and elbow-le-

vers. Fig. 4 is a detail side elevation of the ribbon-feed ratchet-and-pawl mechanism.

Referring to the drawings and noting Fig. 1 thereof, the key-levers B are pivoted at B² to the frame A of the machine, and a pin C² upon the key-lever B engages a slot in one arm of an elbow-lever C, which elbow-lever is fulcrumed at C' upon the frame A. Upon a key-lever B being pressed its motion is imparted to its respective elbow-lever C. Each of the elbow-levers C has an upwardly-extending arm which is connected by a pin-and-slot device with its respective type-bar or impression device D. Each of the elbow-levers C also has a rearwardly-extending shoulder C³, which is normally in close proximity to a universal bar E' and engages said bar E' to operate it upon the depression of the proper key-lever. The universal bar E' lies substantially parallel to the upper surfaces of the several shoulders C³ and transversely of said shoulders, as well as substantially parallel to the general plane of arrangement of the several key-levers B. The universal bar E' forms the forward side of a universal-bar frame which also comprises arms E², connecting the bar E' with a sleeve E², which is substantially parallel to the said bar. The sleeve E² is mounted upon a stationary rod e, which is secured to the frame A, preferably near the pivots of the key-levers B, and forms the pivot for the universal-bar frame. The universal-bar frame is further provided with two upstanding arms E⁶ E⁶, which are joined at the top by a top bar E⁷. A small frame E³, mounted upon the bar E⁷, carries the escapement K, which may be of any suitable form to coöperate with the rack N' on the carriage N of the type-writer and be operated by the oscillation of the universal-bar frame. The spring H, acting upon the angle-lever G and thence upon the arm F, which is rigidly secured to the sleeve E², secures the return of the universal-bar frame to its normal position.

From the top of the universal-bar frame an

arm E^4 projects forwardly, in which arm E^4 a vertical slot E^5 is provided. A lever I is fulcrumed at I^2 upon a bracket A^3 of the frame A , one arm of which lever I carries a pin I' , which engages the slot E^5 in the arm E^4 . The other arm of the lever I is bent around and is pivotally connected with a vertically-movable central ribbon-guide J , which supports the ribbon adjacent to the printing-point, this ribbon-guide J being mounted for substantially vertical reciprocation in front of the platen upon the frame A . When a key-lever B is pressed, the universal bar E' is operated, and the arm E^4 , through the pin-and-slot connection, operates the lever I to carry the ribbon-guide J upward to the printing position. The release of the key-lever permits the return of the universal bar and the ribbon-guide J .

The ribbon-feed mechanism, as shown, comprises two ribbon-spool holders P^4 on spindles P^3 , which spindles are driven through bevel or miter gears P^2 from shafts P' . Fast upon the shafts P' are mounted ratchet-wheels P , which, as shown, may have their teeth pitched in the same direction, the opposing directions of movement being given the ribbon-spindles P^3 by the unlike disposition of the bevel or miter gears P^2 . Feed-pawls O are pivoted upon upstanding lugs at either end of the universal bar E' , and one of them is normally maintained in active contact with its ratchet P by a spring Q . Retaining-pawls R are pivoted upon the frame A and pressed toward the ratchets P by springs S . The ribbon-feed mechanisms beyond the universal bar E' are substantially duplicates, except in that the bevel or miter gears P^2 are arranged to impart opposing directions of movement to the respective spools. Only one of these duplicate mechanisms may operate at a time, and therefore a suitable mechanism is employed to render one of them inactive. Thus I have shown a switch T , fulcrumed at the center of the machine at T' and having arms T^2 , which extend over projections of the retaining-pawls R . When one end of the switch T is depressed, it swings the retaining-pawl R at that end out of active contact with its ratchet. The retaining-pawls R are each provided with pallets R^2 , which extend in contact with their respective feed-pawls O , so that the removal of a retaining-pawl R from active contact with the ratchet also removes its respective feed-pawl O from contact with said ratchet. This switch T may be locked by having a projection thereon engaging a series of notches on a frame portion A^4 , or vice versa. When one end of the switch T is up, the other end is down, and thus only one set of pawls will be in operation at once. It will be seen that the rise of the universal bar E' , carrying the pawls O , one of which is active, will cause said pawl to feed the ribbon from that end of the machine.

By the improved construction hereinbefore

described a simple, accessible, and effective mechanism is provided through which a very light touch is obtained.

What I claim as new, and desire to secure by Letters Patent, is—

1. In a type-writer or other machine, the combination with key mechanism, of a universal-bar frame arranged to be operated by said mechanism, feed-pawls carried by said frame so as to swing therewith, ribbon-feed mechanism arranged to be actuated by said feed-pawls, and retaining-pawls carried by a stationary part and located adjacent to the feed-pawls. 70

2. In a type-writer or other machine, the combination with key mechanism, of a universal bar arranged to be operated by said key mechanism, lugs at each end of said universal bar, feed-pawls pivotally mounted on said lugs, a ribbon-feed mechanism arranged to be actuated by said feed-pawls, and retaining-pawls mounted on a stationary support adjacent to the feed-pawls. 75

3. In a type-writer or other machine, the combination with key mechanism, of a universal bar arranged to be operated by said key mechanism, feed-pawls pivotally mounted at each end of said universal bar, retaining-pawls pivotally mounted on a stationary support adjacent to said feed-pawls, a switch mounted in operative relation to all of said pawls and a ribbon-feed arranged to be actuated by said feed-pawls. 90

4. In a type-writer or other machine, the combination with key mechanism of a universal bar arranged to be operated by said key mechanism, a ratchet ribbon-feed, feed-pawls pivotally mounted at each end of said universal bar, means for bringing said feed-pawls in active contact with said ratchet ribbon-feed, retaining-pawls pivotally mounted on a stationary support adjacent to said feed-pawls, means for pressing said retaining-pawls toward the ratchet ribbon-feed and a switch mounted in operative relation to all of said pawls. 100

5. In a type-writing machine or the like the combination with key mechanism, of a universal bar arranged to be operated by said key mechanism, a ribbon-feed, feed-pawls pivotally mounted at each end of said universal bar, retaining-pawls pivotally mounted adjacent to said feed-pawls and provided with pallets which extend in contact with the feed-pawls and a switch fulcrumed at the center of the machine in operative relation to all of said pawls for throwing the said pawls into and out of engagement with the ribbon-feed. 115

In testimony whereof I have hereunto set my hand in the presence of two subscribing witnesses.

FRANZ X. WAGNER.
